UNITED STATES PATENT OFFICE.

EDMUND M. SAETTELE, OF ST. LOUIS, MISSOURI.

DESIGN FOR AN ORNAMENTAL STAND.

SPECIFICATION forming part of Design No. 35,466, dated December 24, 1901.

Application filed July 22, 1901. Serial No. 69,828. Term of patent 3½ years.

To all whom it may concern:

Be it known that I, EDMUND M. SAETTELE, a citizen of the United States, and a resident of St. Louis, in the State of Missouri, have invented and produced a new and original Design for an Ornamental Stand, of which the following is a full, clear, and exact description.

The accompanying drawing is an elevation of a globe and stand therefor exhibiting my new design.

The leading feature of the design consists in the design forming the subject-matter of the accompanying illustration, in which the globe, on which appears a map of the world, is mounted upon a base having a broad cylindrical bottom portion and two superposed tapering concave portions, and the representation of a sword and a pen appear projecting above the globe.

As shown in the drawing, the pen A is a

writing-pen, and the sword B has its hilt adjacent to the pen. The pen is a reproduction of Jefferson's historic pen and the sword a likeness of a Washington sword.

The globe C, upon which appears a map of the world, is located upon a base D, having the tapering concave portions upon which appear emblems or decorations D' and D''.

Having thus described my invention, I claim as new and desire to secure by Letters Patent—

The design for an ornamental stand, as herein shown and described.

In testimony whereof I have signed my name to this specification in the presence of two subscribing witnesses.

EDMUND M. SAETTELE.
